UNITED STATES PATENT OFFICE.

JOHN TOMEČ, OF TRENTON, NEW JERSEY.

PROCESS FOR MAKING LINOLEUM.

1,161,754.

Specification of Letters Patent. Patented Nov. 23, 1915.

Application filed June 29, 1914. Serial No. 847,903.

To all whom it may concern:

Be it known that I, JOHN TOMEČ, a citizen of the United States, residing at Trenton, in the county of Mercer and State of New Jersey, have invented new and useful Improvements in Processes for Making Linoleum, of which the following is a specification.

The invention relates to an improved process being directed particularly to a method of producing a linoleum product made up of a series of any number of distinctively colored sharply divided sections in an integral formation, so that in producing the commercial product any contemplated geometrically designed pattern may be formed, while avoiding a large number of seam junctures now necessary between sections in forming such configuration.

As heretofore practised, a linoleum strip has been formed of the uniform color, that is each strip is formed from one uniformly colored mass, whereby in forming the geometrical design for the completed product, it was necessary to sever or die the various sections going to make up such design from separate strips and assemble such separate strips in design formation upon a proper backing. There was thus formed between each of said strips a seam, which in the use of the product gradually opened with the consequent disadvantage.

With the present process, the linoleum strip or initial product will be made up of distinctively colored portions forming an integral whole, so that in providing the design the various colored sections heretofore distinct, and separate will be integral, whereby a great number of seams in the commercial product are avoided, whereby not only to increase the life and efficiency of the product but materially cheapens its cost.

In carrying out the process, I contemplate the use of the particular machine, the accompanying illustration and description of such particular machine being indicative of the type and being intended to cover all such types as will lend themselves to the particular process being described.

The invention in the preferred form of details will be described in the following specification, reference being had particularly to the accompanying drawings, in which:—

Figure 1 is a side elevation of the improved machine. Fig. 2 is a plan of the

same. Fig. 3 is a vertical central longitudinal section. Fig. 4 is a perspective view of one of the division plates. Fig. 5 is a plan of the linoleum strip constructed by the improved machine. Fig. 6 is a section on line 5—5 of the same. Fig. 7 is a broken plan, showing the use of the strip in the completed linoleum product.

The improved machine comprises a main frame 1 of any appropriate or desired structure, in which is mounted preferably in longitudinal alignment shafts 2, 3, and 4. On each of the shafts 2, 3, and 4 are mounted rollers, the rollers 5 and 6 mounted respectively on shafts 2 and 3 constituting what will be hereinafter termed feed rolls, while the roller 7 mounted on the shaft 4 constitutes the calendering roll. The rolls are positively driven, the shafts 3 and 4 each carrying gear wheels as 8 and 9, the shafts 2 and 3 also carrying smaller sprockets 10 and 11 connected by sprocket chain 12. The important detail of this positive drive is that the gear 9 is of greater diameter than the gear 8, so that the calendering roll 7 travels at less surface speed than the adjacent feed roll 6. A feed belt 12 of endless type travels over the feed rolls 5 and 6, the former being preferably provided with a surface series of wire bristles 13, whereby to positively advance the belt in the proper direction.

Supported on the frame above the junction of the rolls 6 and 7 is arranged the material receptacle in the form of a box like structure 14 of rectangular outline. The end walls are connected by a rod 15 which immediately overlies the space between the rolls 6 and 7, and mounted for adjustment on this rod is a series of division feed plates 16, each formed with a hollow boss extension 17 provided with a set screw 18, whereby the division plate may slidably engage the rod and be held at any desired position thereon. The lower edge of the division plate is formed with opposing curves 19 to accurately conform to the surface of the respective rolls 6 and 7 so that the division plates form a complete division of the material receptacle for a portion of the height of said receptacle above the rolls. For co-operation with the feed receptacle and as a means for controlling the proper distribution of the material placed therein, I provide longitudinal partitions 20, and horizontal partitions 21 arranged on each side of and immediately below the vertical partition.

The horizontal partitions immediately overlie and rest upon the upper edges of the division plates, the vertical partition dividing the receptacle above the horizontal partition into distinctive material chambers 22 and 23. The material receptacle thus provides longitudinally extending divided material receiving compartments in the upper portion and a series of material receiving 10 transversely disposed compartments in the lower portion.

As a result of the process, there is provided a linoleum strip integrally formed and providing a series of distinctively 15 colored strips or bands either with or without the elongated markings simulating wood grain. The linoleum section is illustrated particularly in Fig. 5, wherein 25 represents the strip as formed by the process and 26 and 27 the distinctively colored portions thereof, it being understood that while two such colors are represented, it will be apparent as previously explained that any number of such colored portions may be provided. 20 In forming the completed or commercial product, as shown at 28 in Fig. 7, the strip 25 is tied or cut along predetermined lines to provide the desired geometrically designed pattern, and in this particular of 25 construction, differs materially from such product as previously constructed. For example, in forming the geometrical outline illustrated in Fig. 7, it is only necessary to cut the strip into rectangular outlines, and 30 each of the sections thus formed include a portion of the figure made up of differently colored portions. In the previous linoleum product, that is differently colored, portions have been cut from different strips, and are 35 joined together by the usual seams while as a result of my process these differently colored portions within the main block are integral. Therefore in the instance shown 40 which is true of all other forms of figure a great many of the usual seams in the commercial linoleum product are avoided and hence not only is the life of the linoleum materially increased in use, but the cost of 45 production materially reduced, in that all

necessity for cutting these individual colored portions, securing them to the back- 50 ing and seaming them is avoided.

The salient feature of the present process resides therefore in forming a strip of linoleum so that it integrally embodies any de- 55 sired number of sharply defining distinctly colored portions, whereby in the formation of the product a material saving in labor and time, together with the product capa- 60 ble of materially increasing service, is secured.

What is claimed is:—

1. The herein described process for con- 65 structing commercial linoleum product con- 70 sisting in forming a distinctively colored integral linoleum strip, dividing said strip on prescribed lines to provide cut sections and securing said sections to the base, the cut sections each including integral dis- 75 tinctively different figure portions.

2. The herein described process of form- 75 ing linoleum consisting in arranging a layer of masses of differently colored lino- 80 leum material in a plastic state and feed- 85 ing said material between spaced forming surfaces, the speed of travel of one of the surfaces being greater than the other.

3. The herein described process of forming linoleum consisting in presenting to 80 moving spaced forming surfaces having 85 different speeds of travel, a mass of lino- 90 leum material made up of differently colored portions.

4. The herein described process of form- 85 ing linoleum consisting in presenting to 90 spaced forming surfaces a mass of linoleum material made up of distinctly colored sec- 95 tions uniformly disposed lengthwise the plane of travel of such mass between the forming surfaces, the movement of one of the forming surfaces being at a different speed from that of the other.

In testimony whereof I affix my signature in presence of two witnesses.

JOHN TOMEČ.
